UNITED STATES PATENT OFFICE.

JOHN ANDERSON DOUGHER, OF PRINCETON, MISSOURI.

RAILWAY SWITCH.

Application filed May 7, 1923. Serial No. 637,223.

To all whom it may concern:

Be it known that I, JOHN ANDERSON DOUGHER, a citizen of the United States, residing at Princeton, in the county of 5 Mercer and State of Missouri, have invented certain new and useful Improvements in Railway Switches, of which the following is a specification, reference being had to the accompanying drawings.

This invention relates to certain improvements in railway switches and it is an object of the invention to provide means of a novel and improved character to constantly urge the switch points in one direction whereby the switch is maintained in one position, preferably closed, should any of the parts of the operating mechanism for the switch become loose and whereby hindrance to traffic is avoided.

It is also an object of the invention to provide a novel and improved means operatively engaged with a point of a switch for constantly urging said point into closed position, said means however being sufficiently yieldable to permit the point to be thrown into open position.

The invention consists in the details of construction and in the combination and arrangement of the several parts of my improved railway switch whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan of a railway switch constructed in accordance with an embodiment of my invention;

Figure 2 is an enlarged sectional view taken substantially on the line 2-2 of Figure 1;

Figure 3 is an enlarged sectional view taken substantially on the line 3-3 of Figure 1;

Figure 4 is a sectional view taken substantially on the line 4-4 of Figure 3, looking in the direction of the arrow;

Figure 5 is a sectional view taken substantially on the line 5-5 of Figure 3, looking in the direction of the arrow.

As disclosed in the accompanying drawings, R denote the rails of a main track line and T denote the rails of a turnout. P denote the switch points or tongues of a conventional type connected by the brace rod 1 and a switch rod 2. As the mechanism for throwing the switch points or tongues forms no part of the present invention a detailed description and illustration thereof is omitted.

Upon loosening of the bolts or other parts comprised in the operating mechanism for the switch it sometimes occurs that the points or tongues P assume a partly open position which is dangerous to traffic and it is therefore important that means be provided to prevent this condition and as herein disclosed I provide means associated with one of the points or tongues P for maintaining said tongue in closed position so that right of way is maintained over the main line. Engaged with the inner side of one of the points or tongues P preferably the point inwardly of but in close proximity to the switch rod 2 is a plate 3 held in applied position in a conventional manner by the bolt 4. The plate 3 overlies the bottom flange of the point or tongue P and is provided at its opposite end portions with the depending arms or lugs 5. The plate 3 at a point between the lugs 5 is provided with an outwardly disposed plate 6 which, together with the adjacent portion of the point or tongue P rests upon the upper surface of a hollow base plate 7. The end portion of the plate 7 adjacent to the plate 3 is provided with an upstanding flange 8 provided with an opening 9 through which the plate 6 is freely disposed whereby said flange serves as a guide for the plate 6 when the switch point or tongue P is moved into either open or closed position.

The base plate 7 adjacent opposite sides thereof is provided with barrels or sleeves 10 in each of which is arranged a retractile member or coiled spring 11 secured at its inner end as at 12 to an end portion of an elongated shank 14 disposed through a lug 5 and also extending within said barrel or sleeve 10. Engaged with the shank 14 are the nuts 15 whereby the shank 14 under the influence of the spring 11 constantly urges the point or tongue P in one direction, said nuts 15 also providing means to regulate the tension of the spring 11 as may be required.

The opposite or outer end of the spring 11

is anchored as at 16 to a cap plate 17 associated with the end of the base plate 7 remote from the flange 9 as is clearly illustrated in Figures 2 and 3. The upper surface of the base plate 7 adjacent to the cap 17 is provided thereacross with an upstanding flange 18 having its inner edge undercut and with which abuts an end portion of a tie plate 19, the opposite end portion of the tie plate 19 being engaged as at 20 with the inner flange of the rail R.

As disclosed in the accompanying drawings the base plate 7 is shown as mounted upon a tie comprised in the track structure 15 and held thereto by the spikes 21 although it is to be understood that the plate 7 may be otherwise positioned or arranged as the requirements of practice may necessitate.

While the springs 11 serve to constantly urge the point or tongue P into closed position as illustrated in Figure 1 yet said springs offer no hindrance or obstruction to said point or tongue P being thrown into open position in order that the train may 25 pass over the turnout. These springs however are of particular importance, as hereinbefore set forth, in the event any portion of the operating mechanism of the switch should become loose as these springs will 30 maintain the points or tongues P in a position whereby the traffic over the main line will be unobstructed or unhindered.

From the foregoing description it is thought to be obvious that a railway switch 35 constructed in accordance with my invention

is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

In combination with a rail and associated switch tongue, a base plate disposed therebeneath, means for attaching the plate to the rail, a sliding plate mounted upon the base plate, means for connecting the sliding plate to the tongue, said base plate being provided with a sleeve, a spring within said sleeve, means for operatively connecting one end portion of the spring to the base plate, and means for connecting the opposite end portion of the spring to the sliding plate, said spring serving to impose tension on the sliding plate to constantly urge the tongue toward the rail.

In testimony whereof I hereunto affix my signature.

JOHN ANDERSON ^{his} X DOUGHER.
